UNITED STATES PATENT OFFICE.

ELBRIDGE G. HOWE, OF MILLBURY, MASSACHUSETTS.

CRATE FOR CARBOYS, &c.

SPECIFICATION forming part of Letters Patent No. 745,015, dated November 24, 1903.

Application filed March 25, 1901. Serial No. 52,665. (No model.)

To all whom it may concern:

Be it known that I, ELBRIDGE G. HOWE, a citizen of the United States, residing at Millbury, in the county of Worcester and Commonwealth of Massachusetts, have invented a new and useful Improvement in Crates for Carboys and Similar Receptacles, of which the following is a specification, accompanied by drawings forming a part of the same, in

10 which—

Figure 1 is a side elevation of a crate for carboys embodying my invention. Fig. 2 is a central sectional vertical view. Fig. 3 is a plan view with the upper section of the crate removed. Fig. 4 is an enlarged detailed view of the latch by which the upper and lower sections of the crate are united, and Fig. 5 is a detached view of one of the clamps for clamping the upper and lower sections of the 20 crate together.

Similar reference-figures refer to similar parts in the different views.

My invention relates to a crate designed to inclose a carboy or demijohn or similar receptacle and protect the same during shipment; and the object of my invention is to provide a safe and strong shipping-crate divided at its central portion into an upper and lower section, which are capable of being 25 separated for the removal of the carboy; and it consists in the construction and arrangement of parts, as hereinafter described, and set forth in the annexed claims.

Referring to the accompanying drawings, 30 1, 2, 3, and 4 denote the vertical corner-posts of my improved crate, to which the bars 5 are attached by nails or screws, forming a rectangular framework adapted to inclose the carboy or demijohn and provided at various points of contact with rubber blocks or 35 cushions 6, attached to the crate and arranged to bear against the receptacle contained therein. The corner-posts 1 2 3 4 are divided at their central sections on oblique 40 lines, the division of the posts 1 2 being denoted by the lines 7 and 8, Fig. 2, and the division of the posts 3 and 4 being denoted by the broken lines 9 10, Fig. 1, forming upper 45 sections 11 and lower sections 12. The corner-posts are so divided on oblique lines that the inner sides of the lower section 12 are the highest, and the oblique ends of the lower

section form, with the connecting-bars 6^a, triangular spaces adapted to receive the triangular ends of the upper section 11. The surfaces 13 of the lower section 12 form seats for the lower ends of the upper section 11, upon which they rest and are held in position by the oblique surfaces 13, the bars 6^a and 6^b. 55

Each of the posts 2 and 4 at diagonally opposite corners of the crate are provided with a latch consisting of a steel strip 14 attached to the lower section 12 of the posts and having a shoulder 15 adapted to be engaged by 65 a shoulder 16 upon an elastic spring 17, which is attached to the upper section 11 of the posts, the two engaging members of the latch having beveled surfaces 18 and 19, which are adapted to slide over each other as the upper 70 section of the crate is placed in position on the lower section. An opening 20 is provided in the side bar 6^c to enable the latches to be disengaged when it is desired to remove the upper section of the crate. In addition to the 75 latches attached to the posts 2 and 4 the upper and lower sections of the crate are held together by means of clamps 21, extending across the inner sides of the bars 6^b and 6^a, with their ends bent at right angles at 22 to 80 overlap the edges of the bars and hold them together. A bolt 23 passes through one of the clamping-bars and carries a nut 24, by which the clamp 21 is held in position. In order to separate the upper section of the crate 85 from the lower, the clamp 21 is loosened by unscrewing the nut 24 until the bent ends 22 are released from the bars 6^b and 6^a and the elastic latches 17 are disengaged, thereby releasing the upper section of the crate and 90 allowing it to be lifted from the lower section. When the upper section of the crate is placed in position, the latches 17 slip over and engage the shoulder 15 of the steel strip 14, thereby locking the upper and lower sections of the 95 corner-posts 2 and 4 together, and the clamps 21 are tightened by screwing the nuts 24 upon the bolts 23.

What I claim as my invention, and desire to secure by Letters Patent, is—

1. The within-described crate comprising corner-posts divided at their central sections on oblique lines with the inner sides of said posts the highest connecting-bars across the 100

oblique ends of said posts forming triangular spaces on one section of the crate to receive the ends of the posts on the other section and means for attaching the sections of the crate together, substantially as described.

2. A centrally-divided crate having corner posts divided on oblique lines with the inner sides of the posts the highest, bars connecting said posts on the lower section and inclosing with said oblique ends triangular spaces forming seats for the oblique ends of the posts

on the upper section, bars connecting the posts on the upper section and clamps inclosing the sides of said post-connecting bars, whereby the upper and lower sections are held together, substantially as described.

Dated this 14th day of March, 1901.

ELBRIDGE G. HOWE.
